UNITED STATES PATENT OFFICE.

ENGELBERT LUDESCHER, OF CHICAGO, ILLINOIS.

ELECTRIC FLASH LIGHT.

1,410,335.

Specification of Letters Patent. Patented Mar. 21, 1922.

Application filed April 12, 1920. Serial No. 373,190.

To all whom it may concern:

Be it known that I, ENGELBERT LUDESCHER, a citizen of the United States, residing at Chicago, in the county of Cook and State of Illinois, have invented a new and useful Electric Flash Light, of which the following is a specification.

This invention relates to electric flashlights, one of its objects being to eliminate the objectionable features of the various designs of flashlights now in use.

Among objectionable features present in the ordinary flashlight is the fact that where a sliding switch is used it readily gets out of order, slides too easily and often, when carried in the pocket, shifts out of proper position. It is furthermore objectionable to have the battery in direct contact with the base of the bulb because the bulb cannot long withstand the hard pressure exerted thereagainst by the battery which is usually pressed by a spring in the case of the flashlight. When the flashlight is handled the spring engaging the battery and pressing it toward the bulb vibrates and allows the battery a slight movement which often causes breakage of the bulb and gives the impression that the bulb is faulty whereas the trouble lies solely in the construction of the flashlight. Furthermore in the usual types of flashlights where brass strips are used as conductors, the strips often get out of place or break and the insulating rings used in connection with the reflector work loose and fail to insulate but allow a short circuit to take place. Furthermore where a spring is used for holding the battery pressed against the bulb the pressure against the cap which carries the spring is such as to cause the threads on the cap soon to spread so that the cap will not properly engage the case and must often be replaced by a new one.

An object of the present invention is to overcome all of the objections above noted by eliminating the usual pressure spring employed for holding the battery against the bulb, by eliminating the insulating ring usually provided at the reflector and by doing away with the brass strips and the sliding switch generally used.

A further object is to provide a novel form of switch having a simple form of snap for holding it normally in inactive position and which switch is durable and safe

and can be easily operated by the pressure of a finger thereagainst.

A further object is to provide a structure of this character which will not exert an objectionable pressure against the bulb and cause injury thereto and which can be used efficiently in connection with either a metallic case or a case of fiber.

With the foregoing and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred forms of the invention have been shown.

In said drawings

Figure 1 is a central longitudinal section through a flashlight embodying the present improvements.

Figure 2 is a section on line 2—2, Figure 1, the lamp being removed.

Figure 3 is a perspective view of the contact strip.

Figure 4 is a section through a modified structure.

Figure 5 is a view of the cross strip of the modified structure.

Referring to the figures by characters of reference 1 designates the case having the usual reflector 2 and lens 3, there being the usual bulb stem 4 threaded into the back portion of the reflector. Arranged diametrically within the casing 1 is a strip 5 having end wings 6 which are fastened to the casing 1 at diametrically opposed points by rivets 7 or in any other desired manner. This strip has a projecting lip 8 constituting a contact.

Secured upon the strip 5 by means of rivets 9 is a folded sheet of insulating material indicated at 10 and mounted on this insulating material is a contact strip 11 one end of which is crimped to provide two V-shaped portions 12 and 13, the portion 13 overhanging and extending beyond the contact lip 8. The other end of the strip 11 is bent back and overhangs the portion 12, forming a contact finger 14 adapted to be engaged by the base of the bulb, as shown 110

in Figure 1. The strip 11 is attached to one thickness only of the insulating material by means of rivets 15 so that it will thus be seen that there is normally no electrical connection between the parts 15 and 5.

A switch housing 16 is secured to the casing 1 and extends over an opening 17 in the wall of the casing. Pivotaly mounted in this housing is a switch 18 one end of which 10 is extended into the opening 17, as shown at 19, while the other end constitutes a finger piece 20 adapted to snap into engagement with one end wall 21 of the housing.

The ring 22 at one end of the casing 1 and 15 which is engaged by the reflector 2 is electrically connected by a wire 23 or the like to the ring 24 engaged by the removable cap at the other end of the casing and which cap has been shown at 25. The battery 26 20 is contacted at one end by this cap 25 while its other end contacts with the strip 5.

It will be obvious that by pressing outwardly on the finger piece 18 so as to disengage it from the wall 21, the end 19 of 25 the switch lever 18 will swing inwardly as shown by dotted lines, thus depressing the contact 13 against the lip 8 so as to complete a circuit through the lamp.

Obviously the structure hereinbefore described can only be used in connection with a fiber casing. Where a metal casing is used a structure such as illustrated in Figure 4 should be employed. In this structure the end of the battery is adapted to contact with 30 a conducting strip 27 which is spaced from the cross strip 29 by a strip 28 of insulating material. The contact strip 30 is secured upon a folded strip of insulating material 31 similar to the strip 10 heretofore described and this strip 30 has a spring finger 32 for engaging the base of the bulb and a contact finger 33 spaced from but movable against one end of the strip 27. Where a metal case is used the inner end of the 35 switch 18 will move against the contact 33 and press it against the end of strip 27 so as to complete the circuit. It will be noted in Figure 1 that the inwardly projecting portion 19 of the switch is provided with a 40 covering 34 of insulating material. This covering will prevent the current from short circuiting through the case 1 when said case is formed of metal. It is of course to be understood that while the insulating material 45 can be used on the part 19 when a fiber case is employed, it is not essential unless a metallic case is used.

What is claimed is:

1. The combination with a casing of insulating material, a combined lamp holder 60 and reflector of conducting material at one end of the casing, a closure of conducting material at the other end of the casing for engaging one terminal of a battery, and an electrical connection between said closure 65 and the reflector, of a cross strip of conducting material within the casing for engaging the other terminal of the battery, a resilient contact strip fixedly connected to but insulated from the cross strip, one end of the 70 contact strip being engageable by the central contact on the base of a lamp in the reflector, a housing on the casing, a switch pivotally mounted in the housing and normally closing the same, and means for fastening the 75 switch in closed position, there being a slot in the casing and opening into the housing, said slot being normally concealed by the housing and switch, one end portion of the switch being movable against the contact 80 strip to shift it against the cross strip when the switch is moved away from normal position relative to the housing.

2. The combination with a casing, a combined lamp holder and reflector of conducting material at one end of the casing, a closure of conducting material at the other end of the casing for engaging one terminal of a battery, such closure being electrically connected to the reflector, of a cross strip 85 90 within the casing for engagement by the other terminal of the battery, and resilient contact strips insulated from the cross strip for engagement by the central contact on the base of a lamp in the reflector, a housing 95 on the casing, a switch pivotally mounted in the housing and normally closing the same, means for fastening the switch in closed position, there being an opening in the casing, and an insulating covering upon a portion of the switch and movable against the contact strip to shift it against the cross strip when the switch is moved away from normal position relative to the housing, said switch, when closing the housing, constituting means for closing the opening in the 100 casing.

In testimony that I claim the foregoing as my own, I have hereto affixed my signature in the presence of two witnesses.

ENGELBERT LUDESCHER.
